UNITED STATES PATENT OFFICE.

ERNEST BRISTOW LE MARE, OF ST. HELENS, ENGLAND, ASSIGNOR TO PILKINGTON BROTHERS LIMITED, OF LIVERPOOL, ENGLAND, A BRITISH COMPANY.

APPARATUS FOR PRODUCING A CONTINUOUS STRIP OF GLASS.

Application filed September 16, 1924. Serial No. 738,045.

To all whom it may concern:

Be it known that I, ERNEST BRISTOW LE MARE, a British subject, and resident of "Merle Wood," Kiln Lane, St. Helens in the county of Lancaster, England, have invented new and useful Improvements in Apparatus for Producing a Continuous Strip of Glass, of which the following is a specification.

- 10 This invention relates to apparatus for producing a continuous strip of glass from molten glass in a tank, and has for its object improved apparatus whereby the strip produced is flat and free from defects.
- 15 A continuous strip of glass has heretofore been produced by allowing molten glass, flowing from an orifice in a tank, or from a conduit therefrom, to fall or flow on to a rolling apparatus so as to form a pool 20 which is carried into the pass of the rolling apparatus. It has been found that the glass at the edges of this pool becomes cooled more than the main mass of glass in the pool and to an extent which injuriously affects 25 the quality and flatness of the strip after rolling.

According to this invention, the edges of the pool are protected from excessive cooling by side walls which extend the whole 30 length of the pool up to the pass of the rolling apparatus.

In the accompanying drawings, Figure 1 is a plan view of the apparatus with the crown of the conduit cut off;

35 Figure 2 is a sectional view through the center of Figure 1;

Figure 3 is a half section on the line A—A of Figure 1;

40 Figure 4 is a section similar to Figure 2 showing the invention applied to an alternative form of glass strip producing apparatus, and

45 Figure 5 is a section similar to Figure 3 showing an alternative form of the apparatus.

Referring to the drawings, 1 is a roller co-acting with a chain-table 2 to form the rolling apparatus. The chain-table 2 is of any known form and is diagrammatically indicated in the drawings only by the straight operative portion. The conduit leading the glass from the melting tank or the like to the rolling apparatus has a crown 3, a floor 4, side walls 5 and a mouth 7. The molten glass 8 flowing along the conduit,

forms a pool 9 on the lower member 2 of the rolling apparatus, and is rolled to form the continuous strip 10.

The pool 9 is confined by the side walls 11 which, in the form of apparatus shown in Figures 1, 2 and 3, extend from the mouth 7 of the conduit to the pass of the rolling apparatus. Heating means are provided to maintain the side walls, or that portion of them in contact with the glass in the pool 9, at a high temperature, consisting in gas jets 12 directing heating gases into conduits 13 in the side walls 11.

In the form of glass strip producing apparatus shown in Figures 1, 2, 3 and 5, the floor 4 of the conduit comes close to the chain-table 2, as shown in Figure 2, but in the form shown in Figure 4, it is some distance above the chain-table 2 and the stream of molten glass falls from the mouth 7 of the conduit on to the chain-table 2. In the latter case the side walls 11 are extended to unite and form a wall 14 at the back of the pool. Alternatively such back wall may be formed as a lip depending from the mouth 7 of the conduit.

Now, in rolling glass from a pool, it is of great importance that the glass in the pool should flow continuously towards the pass of the rolling apparatus at all points of the pool, that is to say, that there should be no backwater in which the glass can form eddies or remain nearly stationary, and no restriction sufficient to cause the glass to build up and fold over on itself. For this reason the contour of the side walls 11 in diverging from the mouth 7 of the conduit or from the point at which the glass falls on to the chain-table 2, is of great importance. The exact contour depends on a number of factors, such as the relative widths of the mouth 7 of the conduit and strip and the speed of the roller, but it has been found that a contour which follows the contour of a pool which is unconfined by side walls, gives satisfactory results.

In order to extend the protection against loss of heat afforded by the side walls 11 to the upper surface of the pool 9 near the edges, the side walls may be curved upwards and inwards as shown in Figure 5, the overhanging portion 15 of the side walls 11 serving to protect the surface of the pool beneath it from radiation and convection.

Instead of the gas jets 12, any known

heating means, such as electric heating conductors embedded in the walls, may be employed to maintain the side walls at a high temperature. Alternatively, the heating means may be confined to bring the side walls up to the requisite temperature and, as shown in Figure 5, they may be dispensed with during the rolling operation and the temperature of the side walls maintained by shielding them in any convenient way such as by packing them with heat-insulating material 16.

The invention is also applicable to strip rolling apparatus in which the lower member of the rolling apparatus is a large roller instead of, as in the before described example, a chain-table. The bottom of the side walls then follows the curve of the large roller, and their contour, as in the case of a chain-table, follows that if an unconfined pool.

Having described my invention, I declare that what I claim and desire to secure by Letters Patent is:—

25 1. In apparatus for producing a continuous strip of glass by rolling glass contained in a pool formed on one member of the rolling apparatus and fed from a melting tank, the combination with the said rolling apparatus of side walls confining the pool up to the pass thereof, and means adapted to maintain the said side walls at a high temperature.

35 2. In apparatus for producing a continuous strip of glass by rolling glass contained in a pool formed on one member of the rolling apparatus and fed from a melting tank, the combination with the said rolling apparatus of side walls confining the pool up to the pass thereof, said side walls diverging from the feeding point of the pool to the pass of the rolling apparatus in curves approximating to those of the edges of an unconfined pool, and means adapted to maintain the side walls at a high temperature.

40 3. In apparatus for producing a continuous strip of glass by rolling glass contained in a pool formed on one member of the rolling apparatus and fed from a melting tank, the combination with the said rolling apparatus of side walls confining the pool up to the pass thereof, said side walls diverging from the feeding point of the pool to the pass of the rolling apparatus in curves approximating to those of the edges of an unconfined pool, and heating means in the side walls adapted to maintain the latter at a high temperature.

45 4. In apparatus for producing a continuous strip of glass by rolling glass contained in a pool formed on one member of the rolling apparatus and fed from a melting tank, the combination with the said rolling apparatus of side walls confining the pool up to the pass thereof, said side walls

diverging from the feeding point of the pool to the pass of the rolling apparatus in curves approximating to those of the edges of an unconfined pool, conduits in the side walls and means directing heating gases into the conduits to maintain the side walls at a high temperature.

5. In apparatus for producing a continuous strip of glass by rolling glass contained in a pool formed on one member of the rolling apparatus and fed from a melting tank, the combination with the said rolling apparatus of side walls confining the pool up to the pass thereof, means adapted to heat the side walls at the start of the operation, and shielding means adapted to restrict the loss of heat from the side walls during the operation.

6. In apparatus for producing a continuous strip of glass by rolling glass contained in a pool formed on one member of the rolling apparatus and fed from a melting tank, the combination with the said rolling apparatus of side walls confining the pool up to the pass thereof, said side walls curving upwards and inwards over the edges of the pool to prevent undue loss of heat at those parts of the pool, and means adapted to maintain the side walls at a high temperature.

7. In apparatus for producing a continuous strip of glass by rolling glass contained in a pool formed on one member of the rolling apparatus and fed from a melting tank, the combination with the said rolling apparatus of side walls confining the pool up to the pass thereof, said side walls diverging from the feeding point of the pool to the pass of the rolling apparatus in curves approximating to those of the edges of an unconfined pool, said side walls curving upwards and inwards over the edges of the pool to prevent undue loss of heat at those parts of the pool, and means adapted to maintain the side walls at a high temperature.

8. In apparatus for producing a continuous strip of glass by rolling glass contained in a pool, the combination of a conduit leading the glass from the source of supply, a rolling apparatus closely adjacent to the conduit and on the lower member of which the glass from the conduit forms a pool, side walls extending from the mouth of the conduit to the pass of the rolling apparatus, and heating means adapted to maintain the side walls at a high temperature.

9. In apparatus for producing a continuous strip of glass by rolling glass contained in a pool, the combination of a conduit leading the glass from the source of supply, a rolling apparatus on the lower member of which the glass from the conduit forms a pool, side walls confining the pool at its edges and uniting to form a wall at the

back of the pool and heating means adapted to maintain said walls at a high temperature.

10. In apparatus for producing a continuous strip of glass by rolling glass contained in a pool, the combination of a conduit leading the glass from the source of supply, a rolling apparatus closely adjacent to the conduit and on the lower member of which the glass from the conduit forms a pool, side walls extending from the mouth

of the conduit to the pass of the rolling apparatus, and curving upwards and inwards over the edge of the pool to prevent undue loss of heat at those parts of the pool, and means adapted to maintain the side walls at 15 a high temperature.

In testimony whereof I have affixed my signature hereto.

ERNEST BRISTOW LE MARE.
